UNITED STATES PATENT OFFICE.

GUSTAVE O. DEGENER, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,187,718.

Specification of Letters Patent. Patented June 20, 1916.

Application filed December 13, 1910. Serial No. 597,121.

To all whom it may concern:

Be it known that I, GUSTAVE O. DEGENER, a citizen of the United States, residing in New York city, in the county of New York and State of New York, have invented certain new and useful Improvements in Combined Type-Writing and Computing Machines, of which the following is a specification.

10 This invention relates to computing machines, and particularly to combined type-writing and computing machines of the kind set forth in application No. 503,643, filed February 12, 1910, in which, upon depressing a typewriter key to write a number, the adding or computing mechanism is automatically operated to add or compute the number that is written on the work sheet. An electric motor supplies the power to turn 20 the computing wheels, and the motor operates through a friction or other clutch, to permit the motor to run constantly. An escapement or indexing mechanism is employed in connection with the numeral keys 25 of the typewriter, to determine, in each instance, how far the computing wheels shall be turned by the motor.

According to the present invention, instead of having the motor circuit constantly 30 closed, it is normally open, and the motor is normally still, and each numeral key of the typewriter has means to close said circuit and start the motor into action to supply the power for turning the computing 35 wheels.

One of the principal advantages of this construction is that the machine is less noisy, as the motor and the gearing are stationary when the keys are not being manipulated.

40 This improvement is of additional importance where a special rapidly-revolving power-shaft is employed for assisting at the tens-carrying operation, since said assisting shaft is connected by a train of gearing to the motor, and by bringing the parts to rest, the noise ceases when the keys are not being operated. The cost of running the motor is materially reduced, as it is only in operation when the computing is being actually done.

50 In the preferred form of the present invention, at the down stroke of any numeral key the motor circuit is completed, and the motor starts to turn. No motion of the computing wheels however occurs at this downward key stroke, as such motion is not per-

mitted by the escapement mechanism until the up-stroke of the key, so that the motor has opportunity to gain speed during the down-stroke and part of the up-stroke of the key. In one form of the invention, the connections are such that the paper carriage of the typewriter controls the let-off of the variable-escapement mechanism of the computing machine, so that said carriage must move at each letter-spacing operation, 60 in order to allow the computing wheels to be turned by the motor, which by this time, has gained the necessary speed. Preferably the breaking of the motor circuit is caused by the motor-driven computing 65 mechanism itself, at the final portion of the operation thereof, so as to insure a continuance of power until the computing operation is completed. Other features and advantages will hereinafter appear. 75

In the accompanying drawings, Figure 1 is a part sectional side elevation of the present improvements applied to a combined typewriting and adding machine such as shown in said application, and known as the 80 Underwood computing machine; the parts including a motor, being in normal positions of rest. Fig. 2 is a sectional elevation of the computing mechanism, showing particularly the mechanism for assisting at 85 the tens-carrying operation. Fig. 3 is a perspective rear view, showing the connection between the numeral keys of the typewriter and the computing mechanism. Fig. 4 is a view to be read in connection with Fig. 90 3, showing the means for enabling the paper carriage or its escapement mechanism to effect the operation of the computing mechanism. Fig. 5 is a sectional diagrammatic view to show the closed switch of the motor 95 circuit.

The typewriter includes letter keys 1 and numeral keys 2, all the keys mounted on levers 3, connected by sub-levers 4 to type-bars 5, to throw the latter back 100 against a platen 6 mounted on a carriage 7 driven by a spring barrel 8 and having a rack 9 engaging a pinion 10 connected to an escapement wheel 11. Each type bar has a heel 12 to push back a universal bar 13, which is connected to dogs 14, 15, working in and out of the escapement wheel 11, to permit the step-by-step feed of the paper carriage under the tension of spring 8. 110

Whenever any numeral key 2 is depressed to throw a type against the platen, its lever 3 moves down a link 16 connected to a bell crank 17, and the latter pulls a horizontal link 18, thereby vibrating a lever 19, to which is pivoted a jack 20, that pushes one of a set of escapement pins or index pins 21 through a primary variable-escapement wheel or index pin wheel 22, so that the pin projects from the other side of the wheel; said wheel being power-driven in a manner presently to be described, and the projected pins engaging one after another, with a four-toothed pinion 23, which is fixed to a shaft 24, the latter carrying a four-toothed secondary escapement wheel 25, which is let off intermittently by reciprocating escapement dogs 26, 27.

The initial movement of the escapement dogs 26, 27 is effected by the down-stroke of the key 2; each lever 19 (of which there are nine, grouped in a circle concentric with wheel 22) adapted to bear against a universal plate or member 28, fixed upon a rod 29; said rod having at one end a collar 30, and the lever 31 having a head 32 between said collar and plate 28, so that any lever 19 is enabled to vibrate the lever 31. This lever 31 is connected by a horizontal link 33 with an arm 34 fixed upon a rock shaft 35, upon which are also fixed the dogs 26, 27.

The initial movement of the arm 34 is to the left at Fig. 3; and upon completion of said movement, a latch 36 is pushed by a spring 37 into a notch 38 provided upon a plate 39 fixed to said rock shaft 35, said plate having a curved edge 40 concentric with said shaft, against which said latch presses idly during nearly all of the initial stroke of arm 34. The arms 34, dogs 26, 27, and the shaft 35 are all locked by said latch against return (under the influence of a spring 41). Said spring 37 is connected to a link 42. The latter connects the latch 36 with a lever 43, fulcrumed at 44 on a fixed part of the machine. To the upper end of the lever is connected a link 45, which is pivoted to a pin 46 projecting from a pallet 47. The described locking movement of the latch 36 under the influence of the spring 37, is accompanied by a vibration of the lever 43, and a movement of the pallet 47 (in its fixed guide 48) into contact with the next tooth 49 of the escapement wheel 11 of the power-driven paper carriage 7. There also occurs during the downward movement of the said key 2, a vibration to the left at Fig. 3, of an upstanding arm 50, also fixed upon said rock shaft 35, and engaging a pin 51 projecting from a bar or slide 52, which is supported in a fixed cylindrical guide 53 (Fig. 5). Upon this slide 52 is a shoulder 54, which vibrates or closes an electrical spring-switch or contact 55, fixed by a screw 56 upon an insulating

block 57; a non-conducting washer 58 being provided upon said switch to be engaged by said shoulder 54. This switch or contact 55 is thereby moved into engagement with a contact 59, secured by a screw 60 to said block 57, and preferably yielding. Wires 61 and 62 lead from 55 and 59 to motor 63. Upon the shaft of this motor 63 may be mounted a friction clutch member comprising three shoes 64 to engage a friction ring 65, to which is fixed a bevel pinion 66, meshing with a bevel pinion 67, the latter upon a shaft 68, which also carries a bevel pinion 69 meshing with a bevel pinion 70. To the latter is fixed a pinion 71, meshing with a pinion 72 fixed upon a shaft 73, which carries the primary variable-escapement wheel 22, whereby said motor is enabled to drive said escapement wheel, as well as to run idly temporarily when said escapement wheel is held against rotation by the pinion 23, shaft 24, wheel 25 and dogs 26, 27.

The bar 52, which closes the motor circuit, is temporarily locked in effective position by a latch 74, actuated by a spring 75; said latch entering a notch 76 in said bar to lock it. The latch is mounted upon a horizontal rock shaft 77. No motion of the computing mechanism occurs at this time, but the motor begins to turn and to gain speed.

Upon relief of the key 2 from pressure, the type bar returns to normal position, the carriage-feeding dogs 14 and 15 also return to normal position, together with the universal bar 13, which permits the paper carriage 7 to be advanced one space under the influence of spring 8; the escapement wheel 11 turning to the extent of one tooth. The pallet 47 is pressed to the left at Fig. 4 by the tooth 49 of the advancing escapement-wheel, thereby forcing the rod 45 to the left, and vibrating the lever 43, and causing the link 42 to pull the latch 36 out of the notch 38, and permitting the spring 41 to return the arm 34, rock shaft 35, and dogs 26, 27 to normal positions. The motor thereupon turns the wheel 22 (and the computing wheels connected thereto and presently to be described) until the next tooth of wheel 25 engages dog 26; at which time the pinion 23 is engaged by the pin 21 that has just been projected by a key 2, as above described; the pin which escapes from pinion 23 being returned endwise by a fixed wiper or cam 21^a, Fig. 3. The bar 52 does not at this time return to normal position, because it is held locked by the latch 74. The loose engagement or connection of arm 50 at 51 permits the return movement of the rock shaft 35 and arm 50, while the switch-closing bar or slide 52 remains stationary in effective position.

Initially, the tooth of secondary escape

ment wheel 25 rests upon the first dog 26. During the down-stroke of the key, said tooth slips off from the dog 26, and onto the dog 27; and at the just-described return stroke of the dogs, said tooth is released from dog 27, thereby liberating the wheel 25, pinion 23 and escapement wheel 22, which turns as aforesaid. The last projected pin contacts with the pinion 23, as just explained, and causes the succeeding tooth wheel 25 to engage the dog 26, thereby again arresting the primary escapement wheel 22.

During the final portion of the advance movement of the tooth of secondary escapement wheel 25, after leaving the dog 27, said arm engages a trip or releaser 78, projecting from the rock shaft 77, and swings the latch 74 out of the notch 76, thus permitting the switch-closer 52 to be returned to the right at Fig. 3, to normal position, under the influence of the spring 79; thus permitting the switch or contact 55 to separate from the contact 59, and break the motor circuit; this occurring, of course, at the completion of the computing operation, so that it is assured that power shall be available throughout the entire computing operation. The motor may then run idly and come to rest. Backward movement of the escapement wheel 22 may be prevented by any suitable back check, as a pawl 80, provided with a spring 81. This pawl locks the index-wheel 22 against rotation in one direction, while the pinion 23 operates with the last set pin 21 to lock the wheel against rotation in the opposite direction. At the operation of any key, said last set pin is withdrawn and hence the index wheel is released and may be advanced by the motor until it is again arrested and locked at the point determined by the key operated.

The connection between the primary escapement wheel 22 and the remainder of the computing mechanism, comprises the pinion 72, the pinion 71, the bevel pinion 70, a pinion 82 in mesh with the latter and fixed upon a horizontal shaft 83, a bevel pinion 84 fixed upon shaft 83 and meshing with a bevel pinion 85 upon a vertical shaft 86, the latter carrying at its upper end a bevel pinion 87 meshing with a bevel pinion 88, which is mounted upon a shaft 89, which carries a master wheel 90, the latter having two teeth 91, which are adapted to mesh with internal gears 92, formed upon computing wheels 93, the latter having also external gears 94 to mesh with gears 95 provided upon number wheels 96. These computing and number wheels are mounted in a carriage 97, suitably supported and connected by a bar 98 to the paper carriage 7 of the typewriter, to travel therewith, while the master wheel 90 does not move in axial direction.

The tens-carrying operation is initiated by a tooth 99, with which each of the computing wheels 93 is provided, and which engages a five-toothed pinion 100, to which is fixed a pinion 101 to mesh with the gear 94 of the computing wheel of next higher denomination. Between 101 and 100 and fixed to both of them, is a five-lobed wheel 102, which is turned (by the tooth 99 as aforesaid) into engagement with a soft-rubber roll 103, which is positively rotated by the motor 63 in a manner presently to be explained. This soft rubber roll 103 turns the wheel 102, to assist at or to complete the tens-carrying operation; and a detent 104, having a spring 105 and a roll 106, may finally complete the rotation of the members 100, 101, 102, and then hold them against accidental displacement; the roll 103 turning idly between adjacent lobes of wheel 102, when no tens-carrying operation is being done, and when the motor is running.

The tens-carrying roll 103 is fixed upon a shaft 107, which, at its outer end, carries a bevel pinion 108, meshing with a bevel pinion 109 on a vertical shaft 110, the latter carrying at its lower end a bevel pinion 111, meshing with a bevel pinion 112 secured upon a horizontal shaft 113, which also carries a bevel pinion 114 meshing with a bevel pinion 115 upon a shaft 116. Said shaft 116 also carries a pinion 117, to mesh with an idle pinion 118, the latter meshing with a pinion 119 fixed upon the motor shaft. The soft rubber roll 103 only runs when the motor is running, and then runs long enough at each operation to assure the completion of the tens-carrying operation. It may even run a while after the index-wheel 22 has stopped, since the motor 63 may continue to revolve idly by momentum after said wheel 22 stops; said motor being capable of rotating independently of said wheel 22 both before and after the rotation of the latter.

When the machine is operated rapidly, the motor, in practice, may never stop; but upon cessation of operation of the machine, the motor comes to rest, and the objectionable noise of the gearing ceases, and a reduction in cost in running the motor is effected. It will be seen that any of the numeral keys 2 of the typewriter throws the motor into action to turn any computing wheel to an extent determined by the key itself. The release of said key will cause the motor eventually to stop.

The contact or switch arm 55 is preferably made of very thin springy metal, which is flexed by the shoulder 54 from its normal open position to the closed position seen at Fig. 5. By making the arm thin, considerable flexing movement thereof may be secured without burdening the finger-keys. Upon the releasing movement of the member 54 effected by the spring 79, the arm 55

- springs away from the contact 59, and the liability of objectionable sparking is nearly or practically eliminated. The arms 55 and 59 are so formed that when 59 is flexed by the pressure of 55 thereon, there is a slight endwise rubbing of 59 upon 55, due to the different paths in which the two tips move. This rubbing keeps the surfaces clean, as is desirable in electrical contacts.
- 10 Variations may be resorted to within the scope of the invention, and portions of the improvements may be used without others. Having thus described my invention, I claim:
- 15 1. In a computing mechanism, the combination with a set of independently operable numeral keys, of a set of computing devices, an electrical motor for operating said computing devices, means controlled by 20 the keys for variably limiting the extent of movement of the computing devices, a normally open circuit for said motor, means for enabling each of said keys to close said circuit, and means dependent upon the operation of the computing devices for opening 25 the motor circuit.
2. In a typewriting and computing mechanism, the combination with a set of numeral keys, of a computing device, means controlled by the keys for variably limiting the extent of movement of the computing device, an electrical motor for operating said computing device, a normally open circuit for said motor, means for enabling each 30 key at the down stroke thereof to close said circuit, means dependent upon the up stroke of the key for enabling said motor to operate said computing device, and means dependent upon the operation of the computing device for opening the motor circuit.
3. In a typewriting and computing mechanism, the combination with a set of numeral keys, of a set of computing devices, means controlled by the keys for variably 35 limiting the extent of movement of the computing devices, an electrical motor for operating said computing devices, a normally open circuit for said motor, means for enabling each key at the down stroke thereof to close said circuit, means dependent upon the up stroke of the key for enabling said motor to operate said computing device, and means dependent upon the operation of the computing device for opening the motor circuit.
4. In a typewriting and computing mechanism, the combination with a typewriter carriage, a set of numeral keys, and letter-feeding devices controlled by said keys for said typewriter carriage, of a computing device, an electrical motor for operating said computing device, means controlled by the keys for variably limiting the extent of movement of the computing device, a normally open circuit for said motor, means for enabling each of said keys to close said circuit, means to enable the letter-feeding 60 devices controlled by said keys for

movements of the carriage to control the operation of the computing device by said motor, and means to enable the computing device to open said motor circuit.

5. In a typewriting and computing mechanism, the combination with a typewriter carriage, a set of numeral keys, and letter-feeding devices controlled by said keys for said typewriter carriage, of a computing device, means controlled by said keys for determining the extent of movement of the computing device, an electrical motor for operating said computing device, a normally open circuit for said motor, a reciprocating escapement device for controlling the computing device, means to enable each of said keys to move said escapement device in one direction to close said circuit, a spring to return said escapement device, a latch to hold said escapement device against return, means dependent upon the movement of the carriage to release said latch, and means dependent upon the movement of the computing device for opening said motor circuit.

6. In a typewriting and computing mechanism, the combination with a typewriter carriage, a set of numeral keys, and letter-feeding devices controlled by said keys for said typewriter carriage, of a computing device, means controlled by said keys for determining the extent of movement of the computing device, an electrical motor for operating said computing device, a normally open circuit for said motor, a universal member operable by any of said keys, a reciprocating escapement device for controlling the computing device, means to enable said universal member to move said escapement device in one direction and to close said circuit, a spring to return said escapement device, a latch to hold said escapement device against return, means dependent upon the movement of the carriage to release said latch, and means dependent upon the movement of the computing device for opening said motor circuit.

7. In a computing mechanism, the combination with a set of numeral keys, of a computing device, an electrical motor for operating said computing device, a universal member operable by any of said keys, means controlled by the keys for variably limiting the extent of movement of the computing device, a normally open circuit for said motor, means for enabling said universal member to close said circuit and permit the motor to operate the computing device, a latch to hold said circuit closing means in effective position, and means dependent upon the movement of the computing mechanism for releasing said latch.

8. In a typewriting and computing mechanism, the combination with a typewriter carriage, a set of numeral keys and letter-feeding devices controlled by said keys for

- 6 **said typewriter carriage, of a computing device, means controlled by said keys for determining the extent of movement of the computing device, and an electrical motor for operating said computing device, a circuit for said motor, said circuit having a normally open switch, a reciprocating escapement device for controlling the computing device, means to enable any of said keys to move said escapement device in one direction, a spring to return said escapement device, a latch to hold said escapement device against return, a switch-closer movable by any of said keys during the depression thereof, a second latch for holding said switch-closer in effective position, a spring for returning said second latch, means dependent upon the movement of the carriage to release the first latch, and means dependent upon the movement of the computing device for releasing the second latch.**
- 10 **9. In a typewriting and computing mechanism, the combination with a typewriter carriage, a set of numeral keys, and letter-feeding devices controlled by said keys for said typewriter carriage, of a computing device, means controlled by said keys for determining the extent of movement of the computing device, an electrical motor for operating said computing device, a circuit for said motor, said circuit having a normally open switch, a universal member operable by any of said keys, a reciprocating escapement device for controlling the computing device, means to enable said universal member to move said escapement device in one direction, a spring to return said escapement device, a latch to hold said escapement device against return, a switch-closer movable by said universal member, a second latch for holding said switch-closer in effective position, a spring for returning said second latch, means dependent upon the movement of the carriage to release the first latch, and means dependent upon the movement of the computing device for releasing the second latch.**
- 15 **10. In a combined typewriting and computing machine, the combination with numeral keys and a traveling carriage with a letter space feed, of a master wheel traveling step by step with said carriage, an electric motor for driving said master wheel, a normally open circuit for driving said motor, means for closing said circuit by the depression of a numeral key, and a latch holding said circuit closed till the escapement of the carriage releases it.**
- 20 **11. In a computing machine, the combination with numeral keys and computing wheels, of a motor for driving said wheels to an extent determined by the numeral keys, a circuit for driving said motor, a switch in said circuit comprising two terminals normally spaced from each other, a**
- 25 **plunger for moving one of said terminals against the other, a spring normally drawing said plunger clear of said terminal, a latch normally tending to engage said plunger to hold it effective against its terminal, and means for positively releasing said latch at the completion of a computation.**
- 30 **12. In a computing machine, the combination with numeral keys and computing wheels, of a motor for turning said wheels, a circuit for driving said motor, a switch in said circuit having its terminals normally spaced, a plunger moved by the operation of a key to move one terminal against the other, a latch tending to hold said plunger effective, an escapement wheel for determining how far said motor shall turn said computing wheels, and means for releasing said latch at the arrest of said escapement wheel.**
- 35 **13. In a computing machine, the combination with numeral keys and computing wheels, of a motor for turning said wheels, a circuit for driving said motor, a switch in said circuit having its terminals normally spaced, a plunger moved by the operation of a key to move one terminal against the other, a latch tending to hold said plunger effective, an escapement wheel comprising settable teeth, means for moving said plunger by the operation of a numeral key to bring one of said terminals against the other, a latch holding said plunger so effective, and means operated by the tooth so set for positively releasing said latch.**
- 40 **14. In a computing machine, the combination with numeral keys and computing wheels, of a master wheel adapted to turn said computing wheels *scrivitum* to an extent determined by said keys, a motor for turning said master wheel, an electric circuit for driving said motor, means operated by the depression of any numeral key for positively closing said circuit, and means operated by the completion of the turning of a computing wheel for positively opening said circuit.**
- 45 **15. In a computing machine, the combination with numeral keys and computing wheels, of a master wheel for turning said computing wheels *scrivitum*, a device operated by said numeral keys for determining how far said master wheel shall turn at the depression of each numeral key, a motor for turning said master wheel, means operated by the depression of a numeral key for positively closing a circuit for starting said motor, and means operated by said key-controlled device for positively opening said circuit when said master wheel has completed its turning.**
- 50 **16. In a computing machine, two latches, an electric contact held closed by both of them, and a wheel governing one of said latches.**
- 55 **17. A computing machine comprising a**

- driving wheel and an index pin which is displaced on said driving wheel, a stop for arresting said wheel by said pin, a latch which holds a circuit closed, means for releasing said latch by said pin, and a motor in said circuit which drives said driving wheel.
18. In a computing mechanism, the combination with a set of independently operable numeral keys, of a set of computing wheels, a member for operating said computing wheels, a rotating electric motor for driving said member, means controlled by the keys for variably limiting the extent of movement of said member and hence of the computing wheels, a normally open circuit for said motor, means for closing said circuit by the operation of a numeral key, and means dependent upon the movement of said member effected by the motor for opening said circuit.
19. In a combined typewriting and computing machine, the combination with numeral keys and computing wheels, of a traveling carriage, an electric motor, an electrical circuit including said motor, an escapement wheel normally held against rotation, a latch for holding said circuit closed, and means for positively releasing said latch by the arrest of said escapement wheel; means being provided to connect the motor to the computing wheels to turn them, but the motor being also capable of rotation independently of the wheels.
20. In a computing mechanism, the combination with a set of independently operable numerals keys, of a set of computing devices, an electrical motor, means controlled by the keys for variably limiting the extent of movement of the computing devices, a normally open circuit for said motor, and means for enabling each of said keys to close said circuit; means being provided to connect the motor to the computing devices to operate them, but the motor being also capable of rotation independently of the devices.
21. In a computing machine, the combination with numeral keys and computing devices, of an electric motor, a normally open circuit for driving said motor, means operated by the depression of said keys to close said circuit and to hold it closed until the movement of each computing device is complete, means normally preventing the computing devices from being driven by the motor, and means dependent upon the up stroke of said keys, for permitting the motor to drive the computing devices.
22. In a combined typewriting and computing machine, the combination with numeral keys and computing devices, of a traveling carriage, means for carrying numbers represented by keys operated into said computing devices, an electric motor adapt-
- ed to drive said means, a normally open circuit for driving said motor, means closing said circuit by the operation of said keys, means dependent upon the motor-driven means, for holding said circuit closed, and means releasable by the letter-feeding movement of said carriage for restraining the motor-driven means from operation.
23. In a combined typewriting and computing machine, the combination with numeral keys and computing devices, of a traveling carriage, means connected with the carriage for carrying numbers represented by keys operated into said computing devices, an electric motor to drive said number-carrying means, a normally open circuit for driving said motor, means for closing said circuit by the depression of one of said keys, a latch holding said circuit closed, means dependent upon the release of said key for permitting said number-carrying means to be driven by said motor, and means for releasing said latch at the conclusion of the operation of said number-carrying means.
24. In a computing mechanism, the combination with a set of numeral keys, of a computing device, an electrical motor for operating said computing device, a universal member operable by any of said keys, means controlled by the keys for variably limiting the extent of movement of the computing device, a normally open circuit for said motor, means controlled by said universal member for closing said circuit and positively holding it closed long enough to permit the motor to operate the computing device, and means operated by the driving of the motor for automatically opening said circuit.
25. In a computing machine, the combination with computing wheels and numeral keys, of a rotating electric motor for carrying into said wheels numbers represented by the keys struck, a normally open circuit driving said motor, and means closing said circuit on the depression of a numeral key arranged to open said circuit when the key is released, said motor having such connection to said wheels as to permit it to continue to revolve idly independently of the wheels at the conclusion of the computing operation.
26. In a computing machine, the combination with numeral keys and computing wheels, of a motor, means actuatable thereby for driving said wheels to an extent determined by the numeral keys, a normally open circuit for driving said motor, a switch in said circuit comprising two terminals normally spaced from each other, a closer operable by any key for moving one of said terminals against the other, a spring normally drawing said closer clear of said terminals, a latch for holding said closer against said

terminals, and means dependent upon the operation of the motor for releasing said latch.

27. In a computing mechanism, the combination with computing and numeral keys, said wheels controllable one after another by said keys, of carry-over mechanism, a motor, a shaft normally at rest, and means connected to said motor for causing said 10 shaft to turn a part of said carry-over mechanism on each depression of a numeral key, said motor being rotatable independently of the computing wheels, to run idly after the completion of the operation of the latter, 15 whereby the operation of a succession of carry-over trains may be completed.

28. In a combined typewriting and computing machine, the combination with computing wheels and numeral keys, of a master 20 wheel engaging said computing wheels successively, a carry-over mechanism for said computing wheels comprising parts partly or initially moved with said computing wheels, a motor, a shaft arranged to be rotated by said motor to complete said motion of said carry-over mechanism, but normally at rest, and power means arranged to rotate said shaft on the depression of each numeral key; means being provided to connect the 30 motor to the master wheel to turn it, but the motor being also rotatable independently of the master wheel, to run idly after the completion of the movement of the latter, to complete the motion of said shaft.

35 29. In a combined typewriting and computing machine, the combination with computing wheels and numeral keys, of a master wheel to engage said computing wheels successively, a carry-over mechanism for 40 said computing wheels comprising parts partly or initially moved with said computing wheels, a shaft arranged to be rotated to complete said motion of said carry-over mechanism, a motor for rotating said shaft and driving said master wheel, a normally open circuit for said motor, and means for closing said circuit on the depression of each numeral key, and holding it closed until the computing wheels are completely turned; said motor being capable of running idly independently of the master wheel at the conclusion of the movement of the latter, for completing the movement of said 50 carry-over mechanism.

55 30. In a computing machine, the combination with an electric motor, of computing wheels, numeral keys, a master wheel constantly tending to be rotated by said motor when the latter is active, to turn said computing wheels through distances determined by said numeral keys, a normally open circuit for driving said motor, and means controlled by the keys for closing said circuit and holding it closed until the computing 60 wheels are completely turned; the motor be-

ing rotatable independently of the master wheel.

31. In a computing mechanism, the combination with a set of independently operable numeral keys, of a set of computing wheels, an operator for said computing wheels, an electric motor for driving said operator, means controlled by the keys for variably limiting the extent of movement of the computing wheels, a normally open circuit for 70 said motor, and automatic means controlled by the keys for closing said circuit and holding it closed independently of the keys, until the completion of the movement of the operator. 75

32. In a computing machine, the combination with a numeral key, of a wheel forming part of a computing train, an electric motor to rotate said wheel, means for closing a circuit to start said motor by the depression of said key, means controlled by the key for controlling the operation of said wheel, and means dependent upon the completion of the movement of said wheel for breaking said circuit. 80

33. In a computing machine, the combination with computing wheels and numeral keys, of a rotating electric motor for carrying into said wheels numbers represented by the keys struck, a normally open circuit 95 for driving said motor, and numeral-key controlled means for closing and opening the circuit; said motor connected to said wheels by means which permit it to continue to revolve idly independently of the wheels at the conclusion of a computing operation. 100

34. In a computing machine, the combination with computing wheels and numeral keys, of a rotating electric motor, a normally open circuit for driving said motor, 105 means controlled by the numeral keys for closing said circuit, means also controlled by the numeral keys and effective subsequently to the closing of said circuit, for causing the computing wheels to be driven 110 by said motor, to carry into said wheels numbers represented by the keys struck, said motor being capable of rotation while the computing wheels are at rest; and automatically operating means for opening said circuit at the conclusion of each computation. 115

35. In a computing mechanism, the combination with a set of independently operable numeral keys, of a set of computing devices, a rotating electrical motor, means whereby said motor may be caused to drive said computing devices, said motor being also capable of rotation independently of said computing devices, means controlled by the keys for variably limiting the extent of 120 movement of the computing devices, a normally open circuit for said motor, and means for enabling each of said keys to close said circuit. 125

36. In a computing mechanism, the com- 130

- bination with a key-controlled index-wheel, of means normally locking the wheel against rotation in either direction, an electrical circuit including a motor, to drive said wheel, said circuit normally open, key-controlled means for closing said circuit and releasing said wheel so that it may be driven by said motor, and means for opening said circuit concomitantly with the arrest of the 10 index-wheel.
37. In a computing machine, the combination with computing wheels and a master wheel, of numeral keys, a carry-over mechanism for said computing wheels and controlled thereby, a rotatable motor for actuating said master wheel, means whereby a current is connected to drive said motor on the depression of any numeral key and is later disconnected, means to connect the 15 motor to the master wheel to turn it, the motor being also rotatable independently of the master wheel, and a power shaft for driving the carry-over mechanism, connected to be driven constantly by the motor while 20 it rotates, whereby a succession of carry-overs may be effected.
38. In a combined typewriting and computing machine, the combination with type-operating numeral keys and a gang of computing wheels, of a letter-feeding carriage, a master wheel adapted to turn said computing wheels *seriatim* to an extent determined by the numeral key depressed, carry-over devices controlled by said computing 25 wheels, a normally idle power drive for said carry-over devices, and means for making said power drive effective on and after the actuation of any numeral key.
39. In a combined typewriting and computing machine, the combination with type- 30
- operating numeral keys and computing wheels, of a letter-feeding carriage, a master wheel for turning said computing wheels *seriatim*, carry-over devices controlled by said computing wheels, an electric motor for 35 driving said carry-over devices, adapted to rotate idly, and means for connecting a current to drive said motor at the actuation of any numeral key.
40. In a combined typewriting and computing machine, the combination with numeral keys and computing wheels, of a letter-feeding carriage, a master wheel for turning said computing wheels, carry-over wheels for said computing wheels adapted 45 to be initially turned thereby, a shaft adjacent said carry-over wheels adapted to rotate continuously but normally idle, a motor for driving said shaft, and means for connecting a current to drive said motor by the 50 actuation of any numeral key and for automatically disconnecting said current.
41. In a combined typewriting and computing machine, the combination with numeral keys and computing wheels, of a letter-feeding carriage, a master wheel for turning said computing wheels *seriatim*, carry-over wheels for said computing wheels adapted to be initially turned thereby, a shaft adapted to complete the turning of 55 said carry-over wheels but normally idle, a motor for driving said shaft, and means for connecting a current for driving said shaft by the actuation of any numeral key and for automatically disconnecting said current.
42. In a combined typewriting and computing machine, the combination with numeral keys and computing wheels, of a letter-feeding carriage, a master wheel for turning said computing wheels *seriatim*, carry-over wheels for said computing wheels adapted to be initially turned thereby, a shaft adapted to complete the turning of 60 said carry-over wheels but normally idle, a motor for driving said shaft, and means for connecting a current for driving said shaft by the actuation of any numeral key and for automatically disconnecting said current.
